ANTENNA

Luke E. Closson, Detroit, Mich., assignor to Philco Radio and Television Corporation, Philadelphia, Pa., a corporation of Delaware

Application March 25, 1942, Serial No. 436,207

4 Claims. (Cl. 250—33)

This invention relates to radio antennae, and more particularly to a novel cowl-type antenna for motor vehicles and the like.

The object of the invention is to provide a novel antenna structure which reduces the use of metal to a minimum, and which is simple in construction, light in weight, capable of economic manufacture, and efficient in operation.

The invention may be clearly understood by reference to the accompanying drawing, in which

Fig. 1 is a longitudinal sectional view of one form of antenna constructed according to the invention;

Fig. 2 is a greatly enlarged transverse sectional view taken along line 2—2 of Fig. 1;

Fig. 3 is a longitudinal sectional view of an alternative form of the antenna;

Fig. 4 is a greatly enlarged transverse sectional view taken along line 4—4 of Fig. 3; and

Fig. 5 is a slightly enlarged transverse sectional view taken along line 5—5 of Fig. 3.

Referring first to Figs. 1 and 2, the antenna comprises a tapered rod formed of insulating material 1, a conducting wire 2 extending longitudinally within the rod and completely enclosed thereby, and suitable means 3 for supporting the antenna and for effecting electrical connection to the wire 2. In the form of the device shown in Figs. 1 and 2, the rod comprises complementary longitudinal sections 4 and 5 (see Fig. 2) which may take the form of flexible wooden strips provided with complementary longitudinal grooves to accommodate the conducting wire 2. The strips may be semi-circular in cross-section, as illustrated, or they may have any other desired contour. The conducting wire may be an ordinary bare copper wire of small diameter. The assembled parts may be held together by suitable retainers 6 and 7 at the opposite ends of the rod. The retainer 6 is preferably in the form of a ball having a recess so that it may be forced over the top end of the rod. This ball may be formed of any suitable material, such as plastic material, metal, wood, etc. The lower retainer 7 may be in the form of a cap adapted to be forced over the lower end of the rod, and this retainer may also be formed of any suitable material. As shown in Fig. 1, the wire 2 terminates short of the ends of the rod and is completely encased therein. If desired, the exterior of the rod may be covered with a suitable covering 8 to improve the appearance of the device and to prevent moisture from being absorbed by the insulating material or from seeping inward between the sections thereof. This covering may be formed of

fabric or any other suitable material. Of course, the exterior surface may be treated in any other manner; for example, a coating of paint may be applied thereto.

5 In the form of the device shown in Figs. 3 and 4, the rod is molded of insulating material 9 within which a conducting wire 10 is embedded. The material 9 may be any moldable flexible insulating material, such as known forms of plastics having a high dielectric constant, good weather resistant qualities, and sufficient strength. Thus, in this instance, the insulating body of the rod is entirely solid and does not require the retainers at its ends, although the upper end of the rod 10 is preferably ball-shaped, as shown in Fig. 3. Furthermore, in this instance, the exterior surface of the rod does not require any treatment, although it may be treated in any desired manner for improvement of appearance or other purpose.

20 In each of the illustrated forms of the device, the means 3 for supporting the rod and for effecting electrical connection to the wire may comprise a metal mounting bolt 11 having a sleeve 25 or collar 12 at one end embracing the conducting wire, as clearly shown in Fig. 5, and preferably soldered thereto to insure a good electrical connection. The sleeve 12 is embedded in the insulating body of the rod and the shank of the bolt 30 extends transversely externally of the rod, as illustrated. In order to mount the antenna on the cowl 13 of a motor vehicle or the like, a stand-off insulator support 14 may be provided. The shank of bolt 11 may extend through the insulator 35 and through a suitable insulating washer 15. The end of the bolt on the inside of the cowl will then serve as a terminal to which a lead-in wire may be connected.

It will be obvious that the bolt 11 may be readily 40 assembled with the other parts of the antenna during manufacture thereof. It is only necessary to slide the conducting wire through the sleeve 12 and then embed the sleeve in the insulating material along with the wire. In the case of the 45 first form of the device, the insulating sections 4 and 5 will be suitably recessed to accommodate the sleeve 12; while in the second form of the device, the sleeve 12 will be embedded in the insulating body when the latter is molded.

50 From the foregoing description, it will be seen that the invention provides a very simple, inexpensive structure in which just sufficient metal is employed to provide an antenna having good pick-up characteristics, without relying on metal 55 for the strength and resilience desired in this

type of structure. Although it is not adjustable, the antenna rod may be made of suitable length to meet all requirements and, since it may be extremely flexible, its fixed length is unobjectionable.

It will be understood, of course, that the invention is not limited to the specific forms illustrated, but is capable of other embodiments within the scope of the appended claims.

I claim:

1. A pole-type antenna structure, comprising an elongated flexible rod formed of insulating material, a conducting wire extending longitudinally within said rod and enclosed thereby, said rod being substantially solid except for the space occupied by said wire, and a supporting and connecting member having a portion embedded in said rod and engaging said wire, said member extending laterally to the exterior of said rod.

2. A pole-type antenna structure, comprising an elongated flexible rod formed of insulating material, a conducting wire extending longitudinally within said rod and enclosed thereby, said rod being substantially solid except for the space occupied by said wire, a supporting and connecting member having a portion embedded in said rod and engaging said wire, said member extending laterally to the exterior of said rod, and an insulator support recessed to seat said rod

and having an opening through which said member may extend.

3. A pole-type antenna structure, comprising an elongated flexible rod formed of insulating material, a conducting wire extending longitudinally within said rod and enclosed thereby, said rod being substantially solid except for the space occupied by said wire, a supporting and connecting member having a portion embedded in said rod and engaging said wire, said member extending laterally to the exterior of said rod, and insulating support means for mounting said rod on an apertured wall, said member being adapted to extend through the wall and constitute a connecting terminal.

4. A pole-type antenna structure, comprising an elongated flexible rod formed of insulating material, a conducting wire extending longitudinally within said rod and enclosed thereby, said rod being substantially solid except for the space occupied by said wire, a supporting and connecting bolt having a sleeve-like head embedded in said rod and embracing said wire, the shank of said bolt extending laterally to the exterior of said rod, and means including said bolt for securing said rod to an apertured wall, the shank of the bolt being adapted to extend through said wall and constitute a connecting terminal.

LUKE E. CLOSSON.
